ATTORNEY

UNITED STATES PATENT OFFICE.

MARY LOYD, OF PHILADELPHIA, PENNSYLVANIA, ASSIGNOR TO LOEB,
LIPPER & CO., OF SAME PLACE.

DESIGN FOR TRIMMING.

SPECIFICATION forming part of Design No. 26,601, dated February 2, 1897.

Application filed December 22, 1896. Serial No. 616,667. Term of patent 7 years.

To all whom it may concern:

Be it known that I, MARY LOYD, a citizen of the United States, residing in the city and county of Philadelphia, State of Pennsylvania, have invented and produced a new and original Design for Trimming, of which the following is a specification, reference being had to the accompanying drawings, forming part thereof.

10 The leading feature of my design for trimming is a latticed body and a spiral head thereon.

Figure 1 represents a face view of a piece of trimming embodying my design. Fig. 2 15 represents an end view thereof.

In the drawings, A designates the body of the trimming, and B designates the head thereof. The body is formed of crossed strips C, as a lattice, and the head is of spiral form. The ends of the crossed strips are connected, 20 forming loops D.

What I claim is—

The design for trimming substantially as shown and described.

MARY LOYD.
